US00D990889S

(12) **United States Design Patent** (10) **Patent No.:** **US D990,889 S**
Sullivan et al. (45) **Date of Patent:** **** Jul. 4, 2023**

(54) **SUITCASE**

(71) Applicant: **YETI Coolers, LLC**, Austin, TX (US)

(72) Inventors: **Derek G. Sullivan**, Austin, TX (US);
Steve Charles Nichols, Austin, TX (US); **Christopher Kalek**, Austin, TX (US)

(73) Assignee: **YETI Coolers, LLC**, Austin, TX (US)

(**) Term: **15 Years**

(21) Appl. No.: **29/829,880**

(22) Filed: **Mar. 8, 2022**

Related U.S. Application Data

(63) Continuation of application No. 29/763,707, filed on Dec. 23, 2020, now Pat. No. Des. 949,569.

(57) **CLAIM**

The ornamental design for a suitcase, as shown and described.

DESCRIPTION

FIG. 1 is a front perspective view of a suitcase showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines depict portions of the suitcase that form no part of the claimed design.

1 Claim, 6 Drawing Sheets
